Re. 21,590

SHORT WAVE SIGNALING

Original Filed April 5, 1932

UNITED STATES PATENT OFFICE

21,590

SHORT WAVE SIGNALING

Nils E. Lindenblad, Port Jefferson, N. Y., assignor
to Radio Corporation of America, a corpora-
tion of Delaware

Original No. 2,027,919, dated January 14, 1936, Se-
rial No. 699,373, November 23, 1933, which is a
division of Serial No. 603,310, April 5, 1932. Ap-
plication for reissue May 25, 1940, Serial No.
337,281

7 Claims. (Cl. 250—36)

This case is a division of my copending applica-
tion Serial Number 603,310, filed April 5, 1932,
and relates to a system for producing ultra short
waves by frequency multiplication.

5 Among the objects of my present invention are
to provide a frequency multiplier in which like
electrodes of a multi-electrode device are both
subjected to fundamental frequency input volt-
ages and simultaneously supply harmonically re-
10 lated output currents; and, to improve the action
of such a multiplier by means of a suitable mag-
netic field.

15 My frequency multiplication action may be
carried into effect by the use of a tube having
a cylindrical split anode, and a linear filament
arranged coaxially with the split anode, the split
anode being in the form of two troughs completely
insulated from each other arranged on either
20 side of the linear filament. Fundamental input
potentials may be applied to the two halves of
the anodes through a simple linear conductor
tunable circuit such as described in my copend-
ing application, and, at suitable points along the
25 conductors, a suitable harmonically tuned cir-
cuit may be connected or coupled thereto. Ap-
plication of the magnetic field in a direction co-
axial with the linear dimension of the filament
will, of course, give the harmonic output in the
30 harmonically related circuit. Preferably, in
such an arrangement, two linear tuned circuits
should be used. Each of the open ends of one
of the circuits should be connected to different
35 ones of the anode sections as should also be
connected the open ends of the conductors of
the other circuit. One of these circuits may then
be adjusted to apply fundamental frequency
energy to the anode sections and the other circuit
40 may be adjusted to have harmonic waves set up
therein. In other words, such a system will
make use of a common linear filament or cathode,
the heating leads for which may be drawn out
45 through the slits between the anode sections and
through the side of the tube at a position inter-
mediate the length of the anode.

Such a frequency multiplying system forming
part of a phase modulation transmitter is illus-
trated in the accompanying drawing.

Turning to it, oscillations from a crystal con-
trolled oscillator 600 are amplified by means of
50 a buffer amplifier 602 in turn supplying energy to
the phase modulator tubes 604, 606, through the
inductive reactance 608A and capacitive react-
ance 610, respectively. Signal frequency energy
is applied to the screen grids 604A and 606A of
55 the tubes 604, 606 in phase opposition through

the intermediary of transformer 608 as a result
of which, the tubes 604, 606 become alternately
more conductive. In this manner, there appears
in the common output circuit 612 constant fre-
quency energy but shifted in phase in accordance
with the signal or audio frequency input applied
to the screen grids of the tubes 604, 606.

The output of circuits 612 is fed to succeeding
amplifiers and frequency multipliers 614, the fre-
quency multiplication action of which serves to
10 augment the phase shift caused by the modula-
tion. When the output of the frequency multi-
plier and amplifier 614 is of desired value, it is
applied to the tuned fundamental frequency in-
15 put circuit 616 of the magnetic frequency multi-
plier 618. Tuning of the fundamental frequency
circuit 616 is accomplished by preferably the use
of adjustable trombone slide 620. The conduct-
ors of the circuit 616 are connected to the split
20 anodes 622, 624, insulated from each other and
arranged concentrically about a coaxial linear
filament or cathode 626 supplied with energy
from a heating source 628. The cathode 626
may be ground, or insulated from ground for
25 extremely high frequencies by means of radio
frequency chokes inserted in the heating leads
from source 628. Magnetic field applied by the
field coil of the magnetic frequency multiplier is
30 applied coaxial with the linear filament 626 and
causes action described more fully in my co-
pending parent application. Briefly, the mag-
netic field causes a decided increase in the har-
monic output, and, in some instances causes out-
35 put where, without the field, no output would
follow.

The field coil produces a magnetic field in ac-
cordance with the current from source 630 regu-
lated by variable resistor 632. The output cir-
cuit 634 of the magnetic frequency multiplier is
40 tuned to a harmonic frequency and also is con-
nected as illustrated to the split anodes. Fre-
quency multiplied energy may then be taken in-
ductively from the output circuit 634 to the ad-
justable transmission line 636 and fed to a suit-
able radiating antenna not shown.

The split anodes may be made of carbon or any
suitable metal and they, together with the fila-
ment, are hermetically sealed within the mag-
netic frequency multiplier container 638.

Having thus described my invention, what I 50
claim is:

1. A frequency multiplier comprising a multi-
electrode device having a cathode and a plurality
of anodes the active surfaces of which are equi-
distantly disposed around said cathode, a tuned 55

circuit tuned to a fundamental frequency connected between said anodes, a tuned circuit tuned to a harmonically related frequency also connected between said anodes, means for supplying energy of fundamental frequency to said circuit tuned to said fundamental frequency, and an output circuit coupled to said tuned circuit tuned to a harmonically related frequency.

2. Apparatus as claimed in claim 1 having in addition means for applying a magnetic field to the electrons flowing from said cathode to said anodes.

3. A high frequency circuit comprising a multi-electrode device having a cathode and a plurality of anodes the active surfaces of which are equidistantly located around said cathode, a circuit tuned to a fundamental frequency connected between said anodes, another circuit tuned to a harmonically related frequency connected between the identical anodes, and means for deriving from one of said circuits output energy of a frequency to which said circuit is tuned when input energy of a frequency harmonically related thereto is impressed upon the other of said circuits.

4. Apparatus as claimed in claim 3 wherein in addition means are provided for subjecting electrons flowing from said cathode to said anodes to a magnetic field.

5. A frequency multiplier comprising a multi-electrode device having a cathode and a plurality of similar cold electrodes symmetrically disposed with respect to said cathode, a tuned circuit tuned to a fundamental frequency connected between said cold electrodes, another tuned circuit tuned to a harmonically related frequency also connected between said cold electrodes, and means for supplying energy of fundamental frequency to said circuit tuned to a fundamental frequency.

6. Apparatus as claimed in the preceding claim characterized by the fact that said circuits consist substantially only of conductors having uniformly distributed inductance and capacity.

7. Apparatus as claimed in claim 5 characterized by the fact that means are provided for subjecting electrodes flowing from said cathode to said cold electrons to a magnetic field.
